UNITED STATES PATENT OFFICE.

CHARLES C. MITCHEL, OF LYNDHURST, NEW JERSEY.

FASTENER FOR RAILWAY-RAILS.

1,076,144.

Specification of Letters Patent. Patented Oct. 21, 1913.

Application filed November 29, 1912. Serial No. 733,959.

To all whom it may concern:

Be it known that I, CHARLES C. MITCHEL, a citizen of the United States, residing at Lyndhurst, in the county of Bergen and State of New Jersey, have invented a certain new and useful Improvement in Fasteners for Railway-Rails, of which the following is a specification.

The invention relates to means for securing railway rails to the ties, and the object of the invention is to provide a fastener by which the rail may be securely attached to the tie without the employment of the usual spikes or bolts engaged with the rail-flange, and which will hold the rail reliably while avoiding the objectionable rigidity attending the use of fasteners of this character, and which may be manufactured and applied economically, and is especially adapted for service with metal ties.

The invention consists in certain novel features of construction and arrangement by which the above objects are attained, to be hereinafter described and pointed out in the claims.

The accompanying drawings form a part of this specification and show an approved form of the invention.

Figure 1 is a plan view of two metal ties and portions of the rails thereon, equipped with the improved fastener. Fig. 2 is a corresponding side view. The remaining figures are on a larger scale. Fig. 3 is a transverse section through a rail and portion of the tie, showing the fastening means in elevation. Fig. 4 is a corresponding central vertical section. Fig. 5 is a top or plan view of a shoe forming part of the fastening means.

Similar letters of reference indicate the same parts in all the figures.

A is the head of the rail and B the tie upon which the rail rests, shown as of metal rolled to channel form with depending flanges B¹ B¹ at the sides, adapted to engage the roadbed and ballast. On each side of the rail and rigidly secured to the upper face of the tie is a plate C held by bolts or rivets C¹ and rabbeted at c on the under face adjacent to the rail to form an overhanging flange C² extending parallel with the rail-base A² and projecting nearly to the edge thereof.

D are shoes which may be malleable castings or rolled steel, of general L-shape in cross-section, each having an upright

flange D¹ shaped on the inner face to match to the contour of the rail-web A¹ and extend to and engage beneath the under face of the rail-head A, and a lateral or horizontal flange D² matching to the upper face of the base-flange A² and extending beyond the latter and beneath the overhanging flange C² of the plate C, to abut against the vertical interior wall of the rabbet c. Each shoe is preferably tapered or inclined on the outer margin of the flange D², as indicated to an exaggerated degree at d in Fig. 5, and both shoes are to be driven by blows of a hammer or other tool into firm frictional or wedging engagement in the rabbet c beneath the flange C² and against the adjacent rail surface. Thus engaged the rail is securely fastened to the tie and held in alignment, but the engagement of the shoes is such as to permit the rail to yield laterally under great train-pressure, to an extremely small extent by reason of the resiliency of the shoe and plate, and thus avoid objectionable rigidity.

Any preferred means may be employed to prevent a reverse movement of the shoes longitudinally of the rail and the consequent loosening of the connection,—that shown consists of a latch E applied behind the shoe when the latter has been driven home with its rear face flush with the adjacent side of the plate. The latch is secured to the plate by a stud-bolt F and may be turned up out of the way, as shown at the left in Fig. 3, while the shoe is being inserted and driven. It is then turned down to cover a portion of the flanges C² and D², with its lower free corner and part of its edge engaged in a slot b provided in the tie at the proper location, and thus locks the shoe in place and effectively bars accidental withdrawal.

Modifications may be made in the forms and proportions as found necessary or desirable in adapting the invention to various types and sizes of rails and conditions of traffic.

The plate C may be bolted to a wooden tie with a tie-plate beneath rail, and other means than the latch may be employed to hold the shoe and plate C in the desired relative positions. The taper or incline of the base of the shoe may be very slight to permit the shoe to be accurately driven to the desired distance.

I claim:

1. In a device of the character set forth, a

- tie, a rail thereon, plates secured to said tie on opposite sides of said rail, each having an overhanging flange adjacent to said rail, a shoe on each side of said rail, each constructed to abut against the web of such rail and the under face of the head thereof, and engage beneath said flange, and pivoted gravitating means for locking said shoe in engagement with said flange.
- 10 2. In a device of the character set forth, a tie, a rail thereon, plates secured to said tie on opposite sides of said rail, each having an overhanging flange adjacent to said rail, a shoe on each side of said rail, each constructed to abut against the web of such rail and the under face of the head thereof, and engage beneath said flange, and a latch pivotally attached to said plate and constructed to lie against said shoe to prevent its movement.
- 15 3. In a device of the character set forth, a tie, a rail thereon, plates secured to said tie on opposite sides of said rail, a rabbet on each of said plates adjacent to said rail, a shoe on each side of said rail, each constructed to match to the base, web and under face of the head of said rail and engage in said rabbet, said shoe having its outer edge inclined lengthwise to produce a wedge-like engagement with said rabbet and rail, and a latch pivotally attached to said plate and constructed to lie against the rear face of said shoe to prevent releasing movements thereof.
- 20 4. In a device of the character set forth, a tie, a rail thereon, plates secured to said tie on opposite sides of said rail, a rabbet on each of said plates adjacent to said rail, a shoe on each side of said rail, each constructed to match to the base, web and under face of the head of said rail and engage in said rabbet, said shoe having its outer edge inclined lengthwise to produce a wedge-like engagement with said rabbet and rail, and a latch pivotally attached to said plate and constructed to lie against the rear face of said shoe to prevent releasing movements thereof.
- 25 5. In a device of the character set forth, a tie, a rail thereon, plates secured to said tie on opposite sides of said rail, each having an overhanging flange adjacent to said rail, a shoe on each side of said rail, each constructed to abut against the web of such rail and the under face of the head thereof, and engage beneath said flange, and a latch pivotally attached to said plate and constructed to lie against said shoe to prevent the withdrawal of the latter, said tie having a slot in which the free end of said latch is received and engaged.
- 30 6. In a device of the character set forth, a tie, a rail thereon, plates secured to said tie on opposite sides of said rail, each having an overhanging flange adjacent to said rail, a shoe on each side of said rail, each constructed to match to the base, web and under face of the head of said rail and engage in said rabbet, said shoe having its outer edge inclined lengthwise to produce a wedge-like engagement with said rabbet and rail, and a latch pivotally attached to said plate and constructed to lie against the rear face of said shoe to prevent releasing movements thereof.
- 35 7. In a device of the character set forth, a tie, a rail thereon, plates secured to said tie on opposite sides of said rail, a rabbet on each of said plates adjacent to said rail, a shoe on each side of said rail, each constructed to match to the base, web and under face of the head of said rail and engage in said rabbet, said shoe having its outer edge inclined lengthwise to produce a wedge-like engagement with said rabbet and rail, and a latch pivotally attached to said plate and constructed to lie against the rear face of said shoe to prevent releasing movements thereof.

8. In a device of the character set forth, a tie, a rail thereon, plates secured to said tie on opposite sides of said rail, each having an overhanging flange adjacent to said rail, a shoe on each side of said rail, each constructed to abut against the web of such rail and the under face of the head thereof, and engage beneath said flange, and a latch pivotally attached to said plate and constructed to lie against the rear face of said shoe to prevent the withdrawal of the latter, said tie having a slot in which the free end of said latch is received and engaged.

In testimony that I claim the invention above set forth I affix my signature, in presence of two witnesses.

CHARLES C. MITCHEL.
